2,186,933

STABILIZATION OF TELEVISION
AMPLIFIERS

Kurt Schlesinger, Berlin-Friedrichshagen, Germany, assignor, by mesne assignments, to Loewe Radio, Inc., a corporation of New York

Original application July 23, 1936, Serial No. 92,151. Divided and this application August 10, 1937, Serial No. 158,390. In Germany July 25, 1935

3 Claims. (Cl. 179—171)

This application is a division of my application 92,151, filed July 23, 1936, which issued as Patent 2,163,219, June 20, 1939.

Photo-cell amplifiers for television transmitters, which are furnished with resistance-condenser coupling or with galvanic coupling and which are also referred to as low-frequency amplifiers, have as is well known the tendency to flutter when operated by mains-connected apparatus or by central batteries. By this there is meant a slow pulsating action at a frequency in the vicinity of the lowest transmission frequency, which is caused by reaction coupling by way of the internal resistance of the anode potential source.

The present invention is directed to low-frequency amplifiers which are also enabled to amplify very low frequencies and in some cases to amplify direct current and shows a method used for these amplifiers for preventing effectively the fluttering effect.

This method will be clearly understood by way of example shown in the accompanying drawing in which there is shown an amplifier circuit for television purposes using a method for preventing fluttering of the anode potential in accordance with the invention.

In this drawing there is shown an exemplary embodiment of the method according to the invention for neutralizing single tube stages against fluttering effect which method is used for screening grid tubes. The fluttering occurs by reason of the fact that the powerful current of one preceding amplifier stage, for example, produces a variation in the anode potential of this feed line 8 via the circuit elements of the feed line 8.

It will be assumed that the feed line 8 experiences a potential fluctuation in the positive direction which, when amplified by the tube (not shown) which is coupled via condenser 25 to tube 24, may lead to fluttering of the amplifier. This disturbance would disappear if it were possible to prevent the anode potential of the tube 24 from fluctuating in conformity with the potential of the feed line 8.

This is attained by coupling the screening grid 26 of the tube 24 to the line 8 so that the screening grid 26 experiences the potential fluctuations of line 8. If the potential of line 8 becomes more positive, the screening grid 26 likewise becomes more positive. This effects an increase of the electron current to the anode 27. Since the electric current is flowing from the anode to the cathode, the potential of the anode of the tube 24 is reduced by an amount which may be made

equal to the increase of its potential due to its connection to the line 8. This compensation depends on the control exerted on the anode current by the screening grid 26, and it is possible to regulate it by varying the degree of coupling of the screening grid 26 to the line 8 until the desired effect is obtained. The operating conditions of the tube 24 necessitate a definite bias for the screening grid 26 which is permanently adjusted by a potential divider 28', 28''. Since by reason of the working conditions of the tube 24 there is a limitation to a certain screening grid bias, it is impossible in many cases to adjust the compensation point by means of ohmic resistance. According to the invention, the adjustment of the compensation may take place by means of a parallel condenser 29. This forms together with the condenser 30 a capacitative potential distribution which, therefore, does not affect the bias conditions of the screening grid 26. By the reduction of 30 and corresponding increases of 29 it is possible in practice to perform a complete stabilisation of the tube 24 in relation to slow fluctuations in the potential of line 8. Rapid fluctuations of line 8 are in any case eliminated in the ordinary way by the filter chain 31/32.

It has been found in practice that a potential distribution of 6:4 mf. for 29:30 in an amplifier having 5 stages and a preliminary tube provided good results, when the screening grid coupling 30 method was employed in the two preliminary stages of the amplifier.

An additional means against fluttering resides in the use of a successive anode current filtering separated according to amplifier groups. This filtering is effected by filter chains, which are to be traversed successively by the anode currents of the single amplifier stages. These filter chains consist of condensers with series resistances or series choke, the number traversed being dependent on how far the amplification stages in the whole amplifier arrangement are situated towards the input end. This additional means is already used in the circuit arrangement shown in Patent No. 2,163,219, issued June 20, 1939.

I claim:

1. A television amplifier circuit arrangement which is also enabled to amplify very low frequencies comprising an amplifier tube having at least four electrodes, a cathode, a control grid, 50 a screening grid and an anode, an input and output circuit for amplifying the television impulses, a common feed line circuit from a bias potential source of fluctuating potential for energizing the electrodes of the tube and coupling means for 55

supplying said screening grid with said potential fluctuations, said coupling means consisting of a circuit connection including a capacitive potential divider in combination with an ohmic potential divider between the feed line and the cathode of said tube, said capacitive potential divider consisting of two condensers connected in series and said ohmic potential divider consisting of two ohmic resistances connected in series and in parallel to said condenser-series connection, the connection point of said condensers and said resistances being connected to the screening grid of said tube, said condensers having such values that the detrimental effect of the bias potential fluctuations is compensated by supplemental variation of the anode current of said tube due to the bias potential variations at the screening grid.

2. A television amplifier circuit arrangement which is also enabled to amplify very low frequencies including a cascade connection of single amplifier stages, each single stage comprising an amplifier tube having at least four electrodes, a cathode, a control grid, a screening grid and an anode, an input and output circuit for amplifying the television impulses, a common feed line circuit from a bias potential source of fluctuating potential for energizing the electrodes of the tube and coupling means for supplying said screening grid with said potential fluctuations, said coupling means consisting of a circuit connection including a capacitive potential divider in combination with an ohmic potential divider between the feed line and the cathode of said tube, said capacitive potential divider consisting of two condensers connected in series and said ohmic potential divider consisting of two ohmic resistances connected in series and in parallel to said condenser-series connection, the connection point of said condensers and said resistances being connected to the screening grid of said tube, said condensers having such values that the detrimental effect of the bias potential fluctuations is compensated by supplemental variations of the anode current of said tube due to the bias potential variations at the screening grid.

3. A television amplifier circuit arrangement which is also enabled to amplify very low frequencies including a cascade connection of single amplifier stages, each single stage comprising an amplifier tube having at least four electrodes, a cathode, a control grid, a screening grid and an anode, an input and output circuit for amplifying the television impulses, a common feed line circuit from a bias potential source of fluctuating potential for energizing the electrodes of the tube and coupling means for supplying said screening grid with said potential fluctuations, said coupling means consisting of a circuit connection including a capacitive potential divider in combination with an ohmic potential divider between the feed line and the cathode of said tube, said capacitive potential divider consisting of two condensers connected in series and said ohmic potential divider consisting of two ohmic resistances connected in series and in parallel to said condenser-series connection, the connection point of said condensers and said resistances being connected to the screening grid of said tube, said condensers having such values that the detrimental effect of the bias potential fluctuations is compensated by supplemental variation of the anode current of said tube due to the bias potential variations at the screening grid.

effect of the bias potential fluctuations is compensated by supplemental variation of the anode current of said tube due to the bias potential variations at the screening grid.

3. A television amplifier circuit arrangement which is also enabled to amplify very low frequencies including a cascade connection of single amplifier stages with a series connection of filter chains in the anode feed supply lines, each single stage comprising an amplifier tube having at least four electrodes, a cathode, a control grid, a screening grid and an anode, an input and output circuit for amplifying the television impulses, a common feed line circuit from a bias potential source of fluctuating potential for energizing the electrodes of the tube and coupling means for supplying said screening grid with said potential fluctuations, said coupling means consisting of a circuit connection including a capacitive potential divider in combination with an ohmic potential divider between the feed line and the cathode of said tube, said capacitive potential divider consisting of two condensers connected in series and said ohmic potential divider consisting of two ohmic resistances connected in series and in parallel to said condenser-series connection, the connection point of said condensers and said resistances being connected to the screening grid of said tube, said condensers having such values that the detrimental effect of the bias potential fluctuations is compensated by supplemental variations of the anode current of said tube due to the bias potential variations at the screening grid, said filter chains consisting of a series connection of series resistances and earthing condensers, which are so arranged that the feed current of the stages which are situated towards the input of the whole amplifier arrangement have to transverse the filter elements of the succeeding stages.
